UNITED STATES PATENT OFFICE.

HENRY W. CARTER, OF PROVIDENCE, RHODE ISLAND.

WATER-HEATER.

No. 921,359.

Specification of Letters Patent.

Patented May 11, 1909.

Application filed June 19, 1908. Serial No. 439,393.

To all whom it may concern:

Be it known that I, HENRY W. CARTER, a citizen of the United States, residing at Providence, in the county of Providence and State of Rhode Island, have invented a new and useful Improvement in Water-Heaters, of which the following is a specification.

This invention has reference to an improvement in water heaters and more particularly to an improvement in portable instantaneous water heaters.

The object of my invention is to improve the construction of a portable water heater whereby the water is heated to the boiling point with greater celerity than has heretofore been done.

A further object of my invention is to simplify the construction of a portable instantaneous water heater, thereby improving the operation and reducing the cost of manufacturing the heater.

My invention consists in the peculiar and novel construction of a portable instantaneous water heater, said water heater having details of construction, as will be more fully set forth hereinafter and claimed.

Figure 1 is a vertical sectional view taken centrally on a line with the inlet and outlet pipes of the heater. Fig. 2, is a view in perspective showing the superheating drum in detached position and a portion of the coil of pipe connected thereto, and Fig. 3, is a horizontal section taken through the casing above the top of the superheating drum, showing the latter in top plan view.

In the drawings, *a* indicates the inlet pipe leading from a source of water supply (not shown) to the water inlet valve *b*, *c* the coil, *d* the superheating drum, *e* the water outlet fitting, *f* the casing of the water heater, and *g* a burner connected to a pipe *h* which may be detachably secured to a pipe leading from a source of gas supply, not shown.

The coil *c* is formed from a pipe *3* which extends from the valve *b* into the casing *f* through a hole in the side of the casing adjacent the lower edge of the casing and is then coiled from the bottom upward toward the top of the casing in the form of a truncated cone, then downward on the inside of the first layer to the starting point and then upward on the inside of the second layer to the top of the same, then outward and upward to the end 4 which is externally screw-threaded, as shown in the drawing.

The superheating drum *d* is in the form of a flat circular drum located in the casing *f* over the coil *c* and having the internal screw-threaded inlet boss 5 on the bottom at one side to which the screw-threaded end 4 of the coil *c* is attached and the oppositely-disposed externally screw-threaded outlet pipe 6 which extends upwardly from the top of the drum *d* through a hole in the top of the casing *f*, as shown in the drawing.

The water outlet fitting *f* is in the form of a goose-neck pipe having the internally-screw-threaded end 7 attached to the outlet pipe 6, thereby clamping the top of the casing *f* between an annular shoulder on the outlet pipe 6 and the end 7 of the fitting *f* and securing the drum *d* to the top of the casing *f*, as shown.

The casing *f* has the closed top 8, the cylindrical sides 9, the open bottom 10, and the legs 11 11 adapted to support the heater in a position to form an annular space between the open bottom of the heater and the surface on which the heater is supported.

The burner *g* is preferably adapted to burn gas, but may be of any form adapted to burn gasoline, naphtha, alcohol or any inflammable substance.

In the operation of my improved water heater the water is turned on by opening the valve *b* and the burner *g* lighted. The heat from the burner *g* rises in the casing *f* through the coil *c* to the top of the casing, where it surrounds the superheating drum *d*. The water is forced through the outer layer of the coil *c* from the bottom upward, then from the top downward through the intermediate layer and then from the bottom upward through the inner layer, then out through the end 4 of the pipe *3* into the superheating drum *d* where it spreads out in a thin layer and from which it is forced outward through the outlet pipe 6 and the outlet fitting *e* into the receptacle for which the hot water is intended.

The water in its passage through the coil *c* and drum *d* is first slightly heated in the outer layer of the coil, then further heated in the intermediate coil, then still further heated in the inner layer of the coil and then brought to hold the greatest intensity of heat in its passage through the thin superheating drum *d* which is located directly above the source of heat energy and is adapted to bring the water to the boiling point or any intermediate degree, controlled by regu-

lating the amount of water passed through the coil *c* and drum *d* and the size of the flame from the burner *g*.

It is evident that the coils forming the coil *c* could be spaced if desired and that any means can be used for detachably securing the pipes *a* and *h* to a source of water and gas supply, without materially affecting the spirit of my invention.

10 Having thus described my invention, I claim as new and desire to secure by Letters Patent;

15 1. In a water heater, a coil formed from a pipe coiled upwardly in the form of a truncated cone, a second coil on the inside of the first coil and connected thereto, a third coil on the inside of the second coil and connected thereto, a superheating drum connected to the upper end of the last named 20 coiled pipe, said drum being composed of a horizontally disposed flat chamber co-extensive with the base of the coils, an outlet pipe connected to the superheating drum, and an open bottom casing having a closed top and 25 sides inclosing the coils and superheating drum.

2. In a water heater, a valve, a coil formed from a pipe connected with the valve and extending upwardly into the heater in the form 30 of a truncated cone, a second coil on the inside of the first coil and connected thereto, a third coil on the inside of the second coil and connected thereto, a superheating drum composed of a horizontally disposed chamber 35 connected to the upper end of the last named coil, an outlet pipe connected to the superheating drum, and an open bottom casing having a closed top, and sides inclosing the coils and superheating drum.

40 3. In a water heater, a valve, a coil formed from a pipe connected with the valve and extending into the heater, said coil extending upward in the form of a truncated cone, a

second coil on the inside of the first coil, and connected thereto, a third coil on the inside 45 of the second coil and connected thereto, a superheating drum, composed of a horizontally disposed chamber coextensive with the base of the coils connected to the upper end of the coiled pipe, an outlet pipe connected to 50 the superheating drum, an open bottom casing having a closed top and sides inclosing the coils and superheating drum, means for heating the coils and superheating drum, and means for supporting the heater in a position 55 to form a space between the bottom of the heater and the surface upon which the heater is supported.

4. In a water heater, a valve, a coil connected to said valve and formed in the form 60 of a truncated cone, said coil being composed of an outer upwardly disposed coil, a second coil on the inside of the said outer coil, and connected thereto, a third coil on the inside of the second coil and connected thereto, said 65 third coil having a screw-threaded upwardly directed end, a horizontally disposed flat superheating drum disposed co-extensive with the base of the coils having an internally screw threaded boss adapted to receive the 70 upwardly directed threaded end of the third coil, an outlet pipe connected to the superheating drum, an outlet fitting in the form of a goose neck, having one end connected to said outlet pipe of the superheating drum, a 75 casing having a closed top, an open bottom, and sides inclosing the coils and superheating drum, and means for heating the coils and superheating drum.

In testimony whereof I have signed my 80 name to this specification in the presence of two subscribing witnesses.

HENRY W. CARTER.
